MAGNETIC CIRCUITS

Fritz R. van der Woude, Elyria, Ohio, assignor to
 The General Industries Company, Elyria,
 Ohio, a corporation of Ohio

Application April 6, 1940, Serial No. 328,346

2 Claims. (Cl. 175—21)

This invention relates to magnetic circuits, and more particularly to an improved construction for magnet cores and the like.

An object of this invention is to provide an improved sectional construction for magnet cores and the like which will contribute to the economical manufacture and assembly of various electrical devices of which cores form a part.

Another object of my invention is to provide an improved core construction in which the core can be formed of separate sections so as to facilitate assembly of the energizing coil or other parts of the device embodying such core and in which the core sections are adapted to be readily assembled to form an efficient and satisfactory core and one in which the core sections are not likely to become loose or accidentally separated.

A further object of my invention is to provide an improved core construction in which core sections are constructed and arranged to form a joint having low magnetic reluctance and in which spring means is arranged to span the joint and acts on the core sections to prevent opening or separation of the joint.

My invention may be further briefly summarized as consisting in certain novel combinations and arrangements of parts hereinafter described and particularly set out in the appended claims.

In the accompanying sheet of drawing:

Fig. 1 is a plan view showing a magnet core constructed according to my invention and embodied in an electrical device;

Fig. 2 is an edge view thereof;

Fig. 3 is a plan view showing another magnet core constructed according to my invention; and

Figs. 4 and 5 are partial plan views showing still other magnet cores constructed according to my invention.

For a more detailed description of my invention, further reference will now be made to the drawing, but before proceeding with the detailed description, I wish it to be understood that the invention is not to be regarded as limited to the particular core constructions and arrangements herein disclosed, since it may be embodied in various other specific forms of magnet cores and in numerous kinds and types of electromagnetic devices.

In Figs. 1 and 2 I show a magnetic circuit constructed according to my invention and comprising a core 10 having an energizing coil or winding 11 thereon. The core in this instance comprises two sections or parts 12 and 13 which, as will be presently explained, are so formed that they can 55

be readily assembled and connected with each other to form a closed magnetic circuit with the coil 11 in the desired location thereon.

The core sections 12 and 13 may be of various sizes and shapes depending upon the construction desired and the intended use of the completed core or magnetic circuit formed thereby. Although I show the core 10 as composed of only two core sections, it will be understood, of course, that it is within the contemplation of my invention to form a magnetic circuit or core of any desired number of parts or sections.

Core sections intended to be assembled or connected in accordance with my invention, such as the core sections 12 and 13, may be formed as solid bodies of magnetic material, but preferably are of a laminated construction, as shown in Fig. 2, and as is usual in electromagnetic devices in general. The laminations for the core sections 12 and 13 may be stamped from sheet steel, or otherwise constructed, and are arranged in stacks in registering relation with each other and may be retained in such relation by suitable rivets 14 or other connecting means extending therethrough.

The core section 12 may have a U-like portion formed by a pair of arms 15 and 16 spaced laterally to receive the coil 11 therebetween, and the core section 13 may be in the form of a straight bar or arm of a length to extend through the coil and to connect the outer ends of the arms 15 and 16 of the core section 12.

The meeting portions of the core sections 12 and 13 may be of any shape or formation which will enable these portions to fit together sufficiently tightly to provide a joint having very low magnetic reluctance. In other words, the meeting portions of these core sections are preferably so formed that they engage or abut each other with metal-to-metal contact and with minimum air space therebetween. Such meeting portions may be in the form of plane faces or can be of irregular shape for mating or interfitting engagement. As indicated in Fig. 1 the meeting portions of the core sections 12 and 13 may be so formed or disposed as to engage each other to form the joint 17 with the adjacent portions of the core sections extending in angular relation to each other, or in other words, with the meeting core portions forming a corner 18 on the core with the joint 17 extending across the corner such as in the diagonal relation illustrated.

For connecting the core sections 12 and 13 with each other in the desired relative arrangement, I employ spring means which draws or

serves to hold the meeting portions of the core sections together in the above-mentioned relatively tight metal-to-metal contact. This spring means may comprise one or more curved springs 19 of the plate or leaf type which are provided with appropriate means or are so shaped as to have gripping engagement with the core portions to be connected. For convenience of manufacture and assembly, the connection between one of the springs 19 and the core sections may be formed by providing the adjacent or meeting core portions with grooves or recesses 20 and providing the spring with hook-like portions 21 adjacent its ends and adapted to engage in these grooves or recesses. The grooves 20 may be formed in the outer edges of the core sections 12 and 13 adjacent the ends of the cooperating arm portions thereof and may be cut or otherwise formed in the core sections so as to extend transversely to the planes of the laminations.

When the spring 19 is to be applied to a joint located at a corner of the core, as in the case illustrated in Fig. 1, the spring may be arranged to span or extend around the corner with the corner extending into the concavity or recess of the spring.

In constructing and assembling the parts constituting the core 10, the core sections 12 and 13 would first be constructed as separate parts as above described, and after placing the coil 11 on the core section 13, the sections would be brought together into the relative positions shown in Fig. 1 with the ends or meeting portions of the sections engaging each other to form the tight fitting joint 11. The springs 19 are then applied to the cooperating portions of the core sections by engaging the hook-like portions 21 of the springs in the grooves or recesses 20. This can be readily done by moving the springs edgewise, that is, at right-angles to the planes of the laminations and thereby sliding or advancing the hook-like portions 21 of the springs along the grooves 20. The spacing of the grooves 20 and the portions of the springs 19 are preferably such that when the springs are applied to the adjacent portions of the core sections in this manner, the springs will be stressed or deflected somewhat so that they will thereafter act to draw or tightly press the meeting portions of the core sections against each other. While the springs 19 may be made of any desired width, I prefer to construct them so as to have a width substantially equal to the thickness of the core sections, as shown in Fig. 2 of the drawing.

My improved core construction is applicable to magnet circuits in general and can be embodied in numerous different kinds of electrical devices. By way of example, Figs. 1 and 2 show my improved core construction embodied in a small electric motor of the shaded pole type. The motor here illustrated has a rotor 22 disposed in an opening 23 of the core section 12 and mounted for rotation therein by means of suitable bearings 24 and 25 in which its shaft 26 is journaled. The bearings 24 and 25 may be carried respectively by bars or plates 27 and 28 which are arranged to extend transversely of the frame opening 23 and may be connected with the frame by screws 29 having spacers 30 thereon. Shading coils 31 may be arranged on the core section 12 adjacent the rotor opening 23 thereof. One or more holes 31a may be provided in the core 10 for connecting the motor with a support or base.

In Fig. 3 of the drawing I show my invention embodied in a magnetic circuit or core 32 which is of ring-like form and which is composed of a multiplicity of core sections 33. Springs 34, 5 similar to the springs 19 above described, may be applied to all four corners of the core 32 for holding the core sections in assembled relation, or if desired, this form of connecting means can be used at certain corners only while a solid or 10 integral construction is provided at the other corners.

My invention is not limited to the use of a connecting spring means at a corner or corners of a magnetic core, but can be used as well for connecting core portions which extend in alignment with each other. Fig. 4 shows one such construction in which core sections 35 and 36 are curved and extend in arcuate alignment with each other and have their adjacent ends connected and held in tight metal-to-metal contact by the spring 37 which may be arranged on the outside of the curve so as to span the joint 38. Fig. 5 shows another such arrangement in which core sections 39 and 40 extend in straight or lineal alignment with each other and are connected by the spring 41 arranged to span the joint 42.

Although the core sections illustrated in Figs. 3, 4 and 5 may be of a solid construction, they are preferably also formed as stacks of laminations disposed in registration with each other and connected by rivets 43 extending therethrough.

From the foregoing description and the accompanying drawing, it will now be readily seen that I have provided an improved construction for magnetic circuits, cores and the like which permits such members to be formed of separate parts so as to facilitate the assembly of the electric devices in which they are embodied and yet makes it possible to quickly and easily connect the core sections in a manner such that the joint between the meeting portions of the core sections has metal-to-metal contact and provides a magnetic path of low reluctance. It will be seen furthermore that in this improved core construction I employ spring means which can be easily applied to the adjacent portions of the core sections so as to span the joint formed thereby and which will serve to permanently draw or hold the core sections in the desired metal-to-metal engagement with each other.

While I have illustrated and described my improved magnetic circuit or core construction in a more or less detailed manner, it will be understood, of course, that I do not wish to be limited to the particular constructions and arrangements herein disclosed, but regard my invention as including such changes and modifications as do not constitute a departure from the spirit of the invention and the scope of the appended claims.

Having thus described my invention, I claim:

1. A core for an electromagnetic device comprising two serially related relatively angularly disposed core elements, each of said elements comprising a stack of elongated flat laminations, the laminations of each stack having similarly formed end edges disposed in complementary transverse alignment, means maintaining the laminations of each core element in fixed relatively superposed stacked arrangement, the aligned lamination edges of one core element abuttingly engaging said aligned lamination edges of the other element, to cause said ele-

ments to substantially define a V, said elements providing the arms thereof, the laminations of each stack each being transversely notched at an edge portion spaced from but near the said end edge thereof with the notches of all said laminations disposed in transverse alignment to provide each of said elements with a transverse groove, said grooves being disposed in parallel spaced relationship at the outer surfaces of, and on the two sides of the apex of said V formation of core elements, and a leaf spring substantially of such U-form as to adapt it to be resiliently expanded to more shallow U-form to snap the ends of the spring into said parallel grooves, said notches and said spring ends being relatively so formed that the retractive spring effect of the expanded spring will prevent said ends from being accidentally dislodged from said grooves, and will resiliently maintain the abutting lamination edges of the members in pressure abutting contact so as to provide a magnetic joint of low permeability.

2. A core for an electromagnetic device comprising two elongated laminated core elements having complementary end face surfaces extend-

ing transversely thereof in surface abutting engagement with the core elements extending angularly divergently from the said abutted surfaces, said surfaces comprising edges of the laminations of said elements, the laminations of each element being transversely notched in alignment to provide a groove, the grooves thereby provided for the respective elements being disposed in substantial relative parallel alignment and disposed in outer relatively diverging faces of the respective elements and in each case near but separated from said abutting surfaces, and a spring provided with a pair of claws, adapted to be resiliently distorted to separate the claws for projection thereof of one said claw in each groove, the retractive effect of said spring resiliently exerting force tending to draw said claws toward each other, and said claws and a wall of each said groove being complementarily so formed with respect to the direction said force is exerted as to retain said claws in their respective grooves, whereby said spring maintains said end surfaces in good abutting magnetic joint making pressure contact.
